UNITED STATES PATENT OFFICE.

PETER EKMAN, OF GREELEY, COLORADO.

ROTARY TRASH-CATCHER.

1,137,469.

Specification of Letters Patent. Patented Apr. 27, 1915.

Application filed December 20, 1912. Serial No. 737,838.

To all whom it may concern:

Be it known that I, PETER EKMAN, a citizen of the United States, residing at Greeley, county of Weld and State of Colorado, have invented certain new and useful 5 Improvements in Rotary Trash-Catchers; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 My invention relates to improvements in rotary trash catchers adapted to be employed in connection with sugar beet flumes through which the beets are passed during the preliminary stage of cleaning them preparatory 20 to grinding and otherwise treating them for sugar making purposes. During this preliminary cleaning stage the beets, together with a suitable quantity of water, are passed through a flume suitably inclined to carry the beets along therewith.

25 Heretofore, so far as I am aware, the only method of removing the trash of various kinds, which clings to the beets, is by direct hand manipulation. In other words, men 30 stand adjacent the flume, and by the use of suitable rakes or catching devices gather the trash and lift it out of the flume. This method of removing the trash is both difficult and expensive.

35 My object is to overcome this difficulty, and to this end, I mount a wheel above the flume, the said wheel being equipped with rakes which are adapted to enter the flume, and when acted on by the water and beets, 40 the wheel is caused to rotate. By virtue of this rotary action the rakes with the gathered trash are carried upwardly on the wheel and automatically drop their contents when they have reached a suitable 45 point above, for the purpose. The trash, as it falls from the rakes, drops upon a stationary shelf mounted upon the frame which supports the wheel. From this shelf the trash may be removed in any suitable 50 manner.

Having briefly outlined my improved construction, I will proceed to describe the same in detail, reference being made to the accompanying drawing in which is illustrated 55 an embodiment thereof.

In this drawing, Figure 1 is a vertical

section taken through my improved rotary trash catcher in a plane cutting the axis of rotation at right angles. This may be termed a section taken on the line 1—1, 60 Fig. 2. Fig. 2, is a vertical section of the structure taken at right angles to Fig. 1, and on the line 2—2, Fig. 1.

The same reference characters indicate 65 the same parts in all the views.

Let the numeral 5 designate a suitable frame work upon the lower part to which is supported a flume or trough 6, having a bottom 7, and upright sides 8. This flume is suitably inclined to cause a stream of 70 water and beets to pass therethrough in the direction of the arrow in Fig. 1. The frame 5, extends above the flume and includes parallel upright members 9, arranged on opposite sides of the flume. Mounted 75 between these members 9, and in alinement with the channel of the flume is a wheel 10, which is supported upon grooved rollers 12, mounted on stub shafts 13, carried by the members 9, of the frame. The wheel as 80 illustrated in the drawing, is composed of two flat circular members 14, arranged in parallel relation and connected by rods or bolts 15, whose opposite ends are threaded 85 to receive fastening nuts 16. Upon each of 85 these rods 15, between the members 14, of the wheel, and pivotally mounted is a number of rakes 17, which are spaced by movable sleeves 18, the rakes being spaced from the wheel members as well as from each 90 other, by means of these sleeves. By virtue of this sleeve structure the two members 14, of the wheel are also spaced from each other. Each rake 17, is composed of two sets of toothed members, 19 and 20. These 95 two sets of members are pivotally connected by a bolt 21, upon which are mounted spacing sleeves 22, which separate the members 19 and 20, on the bolt 21, and also the members 20, from each other. The members 19, are pivotally connected at their extremities remote from the bolt 21, on the rods 15, and spaced by the sleeves 18 heretofore mentioned. The rakes are arranged 100 to swing freely on their supporting rods 15, and the adjacent extremities of the members 19 and 20, also swing freely on the bolts 21. By virtue of this construction each rake is jointed intermediate its extremities. Rods 105 23, extend transversely between the wheel members 14, and connected to the latter rods, are nuts 24, being applied to the oppo-

site extremities of these rods where they extend beyond the wheel members 14. A spacing sleeve 25, is mounted on each rod and interposed between the wheel members 5 whereby the latter are properly spaced. These sleeves, 25, are the true spacing structure for the wheel members 14, since the nuts applied to the rods 23, may be screwed tightly against the outer surfaces of the 10 wheel members. On the contrary, the sleeves 18, which space the rakes on the rods 15, must be loose in order to allow the toothed rake members to move freely. Hence, these sleeves cannot properly space 15 the wheel members to form a solid structure. The sleeves 25, and their supporting rods 23, form a support for the rakes when the latter are upon the upper part of the wheel.

20 In describing the operation of my improved rotary trash catcher, it must be understood (see Fig. 1) that the wheel is traveling in the direction indicated by the arrow *a*. Hence, when the rakes 17, reach a predetermined position on the downwardly moving side of the wheel, (see Fig. 1) the rakes will swing outwardly toward the left, and hang downwardly into the flume, whereby they are brought into the path of the 25 downwardly moving stream of water and beets. Under these circumstances the rakes will occupy such a position with reference to the trash which is carried by the beets, as to catch this trash and separate it from the 30 stream into which the rakes depend.

35 The members of the rakes are toothed in such a manner as to retain the trash as the rakes are carried upwardly on the wheel and when the rakes reach a suitably elevated position, the trash will drop automatically 40 therefrom between the two members 14 of the wheel and fall upon a shelf or platform 26, which is laterally inclined being suitably supported upon the stationary frame work 5, of the structure and extending outwardly 45 beyond the wheel. Attention is called to the fact that this wheel has no axle or support in the line of its center of motion, thus leaving the same clear for the trash to fall from the upper part of the wheel downwardly 50 upon the platform 26.

55 In further explanation of the operation of the structure attention is called to the fact that the rakes are so supported and arranged upon the wheel that when they swing downwardly on the downwardly moving side of the wheel, being the left hand side, referring to Fig. 1, they are flexed as they enter the flume in such a manner that the structure 60 moving through the flume and in engagement therewith can not swing them downwardly since their flexed condition constitutes a lock to maintain the rakes in the trash catching position while the wheel moves sufficiently to carry them upwardly therewith

out of the flume, on the upwardly moving side of the wheel.

Having thus described my invention, what I claim is:

1. In a trash catcher the combination with 70 a frame of a wheel mounted to rotate on the frame, and rakes pivotally connected with the wheel and arranged to hang freely downwardly from the lower part thereof and to serve as paddles against which material passing under the wheel may act to rotate the 75 wheel.

2. In a trash catcher the combination with 80 a frame, of a wheel mounted to rotate on the frame, rakes pivotally connected with the wheel and arranged to hang freely downwardly from the lower part thereof, and means carried by the wheel for supporting the rakes in inverted position when the rakes are on the upper part of the wheel. 85

3. In a trash catcher the combination with 90 a frame, of a wheel supported on the frame, said wheel consisting only of two rings joined together in parallel relation, rollers mounted upon said frame in positions to 95 form a bearing for the wheel, the space enclosed by said rings being free of obstructions and rakes pivotally connected with the wheel and depending from the lower part thereof. 95

4. In a trash catcher the combination with 100 a frame, of a wheel comprising a rim only, said wheel being rotatably supported upon the frame, and rakes pivotally connected with the wheel, and depending from the lower part thereof, the wheel being equipped with means for supporting the rakes in the trash discharging position on the upper part of the wheel. 100

5. A trash catcher comprising a wheel, 105 jointed rakes mounted thereon and composed of toothed members, the rakes being pivotally connected with the wheel, means for supporting the rakes in position to discharge the trash collected thereby from the upper 110 part of the wheel, the rakes being pivotally mounted on the wheel and arranged to assume a depending position on the downwardly moving side for the purpose set forth. 115

6. In a trash collector the combination with 120 a stationary frame, of a wheel mounted thereon, jointed rakes pivotally connected with the wheel and means for supporting the rakes in the trash discharging position when on the upper part of the wheel, the rakes being free to swing downwardly from the lower part of the wheel into the trash collecting position, substantially, as described. 125

7. The combination with a frame carrying 130 rollers, of a wheel composed of two parallel members suitably spaced, the said members engaging the rollers in anti-frictional relation, rakes pivotally mounted between

the two wheel members, rods transversely arranged between the wheel members and forming a support for the rakes on the upper part of the wheel, the rakes being 5 free to swing downwardly from the lower part of the wheel into the trash catching position, and a platform supported within the circle of the wheel which is centrally open to allow the material discharged from 10 the rakes to fall upon the platform from the upper part of the rotary structure, substantially, as described.

8. The combination with a suitable frame carrying rollers, a wheel composed of parallel members, rods connecting the said members, sleeves mounted on the rods and spacing the wheel members, other rods mounted on the wheel members, jointed rakes pivotally connected with the last named rods, 20 and resting upon the spacing sleeves of the first named rods when the rakes are on the upper part of the wheel, the rakes being free to swing downwardly from the lower part of the wheel into the trash collecting 25 position.

9. In combination, an inclined trough, a perpendicularly arranged wheel mounted above and in line with said trough, rakes pivotally attached to said wheel near its 30 circumference and adapted to rest upon the bottom of the trough as they pass in the lower arc of the circle during the rotation of the wheel, said wheel being adapted to be rotated by the passage of material along 35 said inclined trough.

10. In a machine of the character described, the combination with a flume along which tuber-like products associated with trash are carried by a current of water, of a 40 trash catcher, comprising an endless traveling vertically disposed carrier mounted above the flume, said carrier having rakes mounted thereon composed of toothed members, means for supporting the rakes to dis-

charge the trash collected thereby from the 45 upper part of the carrier, the rakes being arranged to assume a depending position on the downwardly moving side of the carrier, and to act as paddles against which the material in the flume may act to move the 50 carrier.

11. In a machine of the character described, the combination with a flume along which tuber-like products associated with trash are carried by a current of water, of a 55 trash collector comprising a stationary frame and an endless traveling vertically disposed carrier mounted thereon, rakes pivotally connected with the carrier, and means for supporting the rakes in the trash dis- 60 charging position when on the upper part of the carrier, the rakes being free to swing downwardly from the lower part of the carrier into the trash collecting position and to act as paddles against which the material 65 in the flume may act to move the carrier.

12. In a machine of the character described, the combination with a flume along which tuber-like products associated with trash are carried by a current of water, of a 70 movable carrier mounted above the flume having trash-engaging elements operating therein substantially in opposition to the flow of water, and foldable links on the carrier and from which said elements are 75 suspended said elements having trash-engaging and retaining surfaces operating in the range of travel of the trash and adapted to separate and remove the trash while allowing the tuber-like products to pass 80 unchecked.

In testimony whereof I affix my signature in presence of two witnesses.

PETER EKMAN.
